(57) **CLAIM**

We claim the ornamental design for a combined wet/dry vacuum cleaner, as shown and described.

DESCRIPTION

FIG. 1 is an isometric front perspective view of a wet/dry vacuum;

FIG. 2 is a front elevational view thereof;

FIG. 3 is a rear elevational view thereof;

FIG. 4 is a side thereof;

FIG. 5 is a side view showing the side opposite that shown in FIG. 4; and,

FIG. 6 is a top view thereof.

The broken lines in the Figures are for the purpose of illustrating exemplary environmental structure and forms no part of the claimed design.
